[57] CLAIM

The ornamental design for a knife handle, as shown and described.

DESCRIPTION

FIG. 1 is a front elevational view of the knife handle of the present invention;

FIG. 2 is a top plan view of the knife handle of FIG. 1;
FIG. 3 is a bottom plan view of the knife handle of FIG. 1;
FIG. 4 is a butt-end view of the knife handle of FIG. 1;
FIG. 5 is a blade-end view of the knife handle of FIG. 1; and,
FIG. 6 is a back elevational view of the knife handle of FIG. 1.

The knife handle is for a utility knife with a blade, which is retractable into the handle.
